POTTERY CASTING MACHINE

Philip Ivor Robinson, Derby, England

Application September 20, 1951, Serial No. 247,409

7 Claims. (Cl. 25—29)

1

This invention relates to the casting of pottery articles.

The object of the invention is to provide a form of installation in which the casting is performed under the immediate control of an operator in such a way that a change-over can be immediately effected from one size or type of article to another, without having to make extensive adjustments or alterations to the means by which the liquid slip is poured into the moulds, and without requiring any measure of skill in the operator.

The invention will be described with reference to the accompanying drawings in which:

Figure 1 is a perspective view showing a mould entering a pouring station.

Figure 2 is a perspective view showing a mould leaving the pouring station.

A traveling chain conveyor 10 is mounted and driven in any convenient way. It is proposed that the conveyor shall extend for some considerable distance to carry the moulds through stations corresponding to various successive operations in the manufacture of the pottery articles. For example after leaving the station shown in the drawings the conveyor would preferably carry the moulds along for a sufficient distance to allow for the casting of the articles to the required thickness, and then the moulds would enter a tipping station where the surplus liquid would be drained out of them. The articles would then at a further station be restored to their normal or upright positions and it might be desired next to trim the edges of the articles at a further station. Then it would be desirable to remove the articles still in the moulds, or perhaps to subject the articles to drying action. Obviously it is unnecessary to illustrate all these stages in the process since they form no part of the present invention. It will be sufficient to say that the conveyor 10 passes over any convenient system of sprockets which are disposed at any suitable intervals, and driving mechanism is applied to some of the sprockets from an electric motor or other source of power. These driving arrangements are situated at a point which may be some distance away from the pouring station and they are therefore not seen in the drawings.

The conveyor 10 consists of a pair of chains spaced a convenient distance apart to give sufficient width, and their direction of travel is indicated in the drawings by arrows 11. Connected across from one conveyor chain to the other are a series of bridge members 12 and each bridge member has associated with it an upstanding

5 abutment whose upper end forms a peak. The abutments are shown at 13 and the peak on each is seen at 13a with the abutment tapered off to a fairly sharp point. Thus it will be apparent that 10 both the bridge members 12 and the abutments 13 are supported by the conveyor chains 10 and move forward with the conveyor. Each bridge member receives and supports a mould carrier 16 in which a mould for the clay article is located, and the mould carrier is mounted in the bridge member in a freely rotatable manner. Associated with the mould carrier 16 is a weighted flywheel 17 at the bottom, and as the conveyor 10 carries the mould carrier through the pouring station this flywheel rides against an endless travelling belt 18 carried on pulleys 19, 20, the belt being driven at a considerably higher speed than the conveyor 10. On leaving the pouring station the flywheel 17 moves clear of the belt 18 15 and comes into contact with a similar travelling belt 21. As indicated by the arrows the belt 21 is driven in the opposite direction, but at about the same speed, as the belt 18. The effect is that during the pouring of slip into the mould 20 the mould is rotated at a suitable speed in one direction, and that after the pouring of slip has 25 ceased the mould is then rotated in the opposite direction.

The slip which is to be poured into the moulds 30 comes from a tank 25. Although for convenience in illustration this is shown as of modest dimensions it will be understood that in practice a fairly large tank is provided. It may be at a point remote from the pouring station. The flow from the tank is through a pipe line 26 which 35 may be a gravity flow, or a syphonic feed, or forced under pressure by the action of a pump or the like. This pipe line 26 terminates at the pouring end in a length 27 of flexible tube which is attached to a union 28 mounted on a bracket 40 structure 29 attached to a carriage 30 running on rollers 31 in inclined ramp rails 32, the slip delivery nozzle 33 passing through a hole 34 in the carriage. The carriage 30 has connected to it arms 35 carrying lugs 36. It has also attached 45 to it a flexible connector 38 which passes round guide pulleys 39, 40, and carries on its free end a weight 41. The nozzle 33 is controlled by a tap 42.

50 The operation of the apparatus is as follows: The handle 43 which operates the tap 42 is normally in an upright position which closes the tap and shuts off the flow of slip through the nozzle 33. As a mould carrier 16 arrives at the 55 pouring station the operator depresses the han-

dle 43 and the flow of slip begins, the mould carrier being rotated meanwhile by the action of the belt 18 and fly-wheel 17. This is the position shown in Figure 1. The abutments 13 at each side of the bridge member 12 of this particular mould carrier now move into engagement with the lugs 36 on the arms 35 on the carriage 30. The effect of this is to push the carriage up the ramp rails 32. The operator allows the slip to be poured until the mould has a sufficient quantity of slip in it, more than sufficient to cast the article required. When this stage is reached the operator turns the handle 43 back to the closed position and the pouring of slip into the mould ceases. Due to the inclination of the ramp rails it will be seen that the carriage and nozzle are gradually being raised as they move forward by the action of the abutments 13 on the lugs 36. Eventually the lugs 36 are level with the peaks 13^a on the abutments, and ride over the peaks, as can be seen in Figure 2 of the drawings. When this happens the carriage 30 and the nozzle 33 ride back down the ramp rails 32, the movement being assisted by the action of the weight 41. The mould carrier meanwhile moves clear of the belt 18 and is presently acted upon by the belt 21, while the next mould carrier moves into the pouring station and the operation is repeated.

It will be seen that the operation is entirely unskilled. All the operator has to do is to turn the tap on when a mould is in position, and turn it off again when enough slip has been poured into the mould. With some kinds of article more slip will be needed than with others but these variations can be immediately made by the operator as each different batch comes along.

I claim:

1. In a casting machine for pottery articles, a pouring station comprising a travelling conveyor, mould carriers supported on said conveyor, inclined ramp rails mounted above said conveyor, a carriage mounted in said ramp rails, a slip pouring nozzle mounted on said carriage, manually operated control means for opening and closing the pouring nozzle, and complementary means on each mould carrier and the carriage engageable to move the carriage along with the conveyor so that the pouring nozzle pours slip into the mould in the carrier so long as the control means allows and until the action of the ramp rails effects disengagement of the means of the carriage from the means of the carrier whereupon the carriage moves back down the ramp rails to its original position.

2. In a casting machine for pottery articles a fixed container for slip, a pipe line from said container leading to a pouring station, a flexible tube connected to the pipe line and to a union, a carriage supporting said union, a pouring nozzle attached to the union, inclined ramp rails in which the carriage is supported for to and fro travel, a travelling conveyor mounted below said carriage and pouring nozzle, a series of mould carriers supported on the conveyor, complementary means on each mould carrier and the carriage for causing the travel of the carriage and nozzle along the ramp rails for a limited distance with

the carrier, and a manually operated control tap associated with the nozzle being arranged to allow the flow of slip through the nozzle into a mould in the mould carrier for a sufficient part of the distance while the carriage and nozzle are advancing with the conveyor.

3. In a casting machine for pottery articles, a travelling conveyor, a series of bridge members supported width-wise on the conveyor, a mould carrier rotatably mounted in each bridge member, means for rotating the mould carriers, each about its own axis, inclined ramp rails mounted over the conveyor, a carriage mounted on the ramp rails, means on each bridge member engaging with said carriage to cause it to travel along with the conveyor for a limited distance until disengaged by the action of the inclined ramp rails, a slip pouring nozzle mounted on the carriage, a manual control for opening and closing the pouring nozzle, flexible tubing connected to the nozzle, and a fixed non-travelling container for slip feeding slip to the nozzle through the flexible tubing.

4. In a machine as claimed in claim 3 the provision of gravity-acting means for assisting the return travel of the carriage down the ramp rails when disengaged from the bridge members.

5. In a machine as claimed in claim 3, the provision of a flywheel on each mould carrier and means engaging said flywheel to impart rotation to the mould carrier in one direction while slip is poured into it and in the opposite direction after the pouring has ceased.

6. In a machine for casting pottery articles, a travelling conveyor, a series of mould carriers mounted on said conveyor, a slip pouring nozzle mounted above the conveyor in alignment with the mould carriers, means above the conveyor and associated with the pouring nozzle for causing the pouring nozzle to advance with the conveyor for a limited distance, means controlling the flow of slip through the nozzle to allow slip to be poured during a sufficient part of the travel of the nozzle and then to shut it off, means for returning the pouring nozzle in the opposite direction at the end of its travel, and flexible means connecting said pouring nozzle with a fixed non-travelling container for slip.

7. A machine as claimed in claim 6 in which the pouring nozzle is mounted on a carriage which travels to and fro along an inclined ramp, the forward travel of the carriage up the incline being effected by means associated with each mould carrier which engages with means associated with the carriage, and the return travel of the carriage down the incline being effected by gravity when the aforesaid means are disengaged from each other.

PHILIP IVOR ROBINSON.
